BALANCED DYNAMIC COMPRESSOR
AMPLIFIEREllison S. Purington, Gloucester, Mass., assignor
to John Hays Hammond, Jr., Gloucester, Mass.

Application April 28, 1948, Serial No. 23,663

1 Claim. (Cl. 179—171)

1

This invention relates to compressor circuits for compressing the dynamic range of the signal in the output circuit of an electronic amplifier and has for an object to provide a circuit of the above type having novel and improved operating characteristics.

Another object is to provide a circuit of the above type having improved efficiency of operation and in which the thump effect and the effect of the control voltage are eliminated.

Various other objects and advantages will be apparent as the nature of the invention is more fully disclosed.

In accordance with the present invention the single-ended dynamic compressor amplifier includes a pair of electron tubes with plates and cathodes connected in parallel, with a common plate feed impedance and a common external output circuit. The input signal is impressed upon the grids of the two tubes in phase opposition but the grid circuits of the two tubes are differently biased so that the outputs are normally unbalanced and an output signal is obtained due to the differential effect of the two outputs. Control voltages are derived from the common output circuit by means of a rectifier network and are applied to the grid return paths of the two tubes in opposite senses so that an increased signal serves to decrease the conductance and plate current of one tube, but increases the conductance and plate current of the other tube in such a manner that the unbalance is decreased with increased signal. Hence the overall gain from source to output is a decreasing function of the signal. This arrangement provides for thump and transient reduction because the changes of space currents in the two tubes are in opposite senses. In addition the dynamic tubes have substantially the same bias and plate currents, approaching class A operation, when the signal through the tubes is a maximum.

The novel features which are characteristic of this invention will be better understood by referring to the following description taken in connection with the accompanying drawings in which a specific embodiment thereof has been set forth for purposes of illustration.

In the drawings the figure is a schematic diagram of a dynamic compressor system embodying the present invention.

In the embodiment shown a pair of dynamic amplifier tubes, indicated as tubes 10, 11 have their plates 10a, 11a connected together and connected through a feed resistor 12 to the positive end of battery 13, the negative end of which is

grounded at 14. The cathodes 10c, 11c of tubes 10, 11 are also connected together and are connected through cathode resistors 15 and 16, bypassed by capacitors 17 and 18, to ground at 19. A bleeder resistor 20 is connected from the positive side of battery 13 to the cathodes of tubes 10, 11. One input terminal 21 of the entire system is connected through a blocking capacitor 22 to the grid 23g of a phase inverter tube 10 23. The other input terminal 24 is connected to ground lead 25. The cathode 23c is connected to ground lead 25 through a self-biasing resistor 26. A resistor 27 is connected across the input circuit. The plate 23a of the tube 23 is connected 15 through a resistor 28 to the positive side of the battery 13, and through a blocking capacitor 29 to the grid 10g of triode 10. The grid 10g is connected to the junction of resistors 15 and 16 through resistor 30 from which it receives its 20 signal voltage, and a resistor 31 from which it receives its automatic control voltage. The resistors 30 and 31 are so related to the resistors 15 and 16 that for weak signals the grid of tube 10 is biased positive with respect to ground but 25 not to cathode potential.

The cathode 23c of phase inverter tube 23 is connected through a blocking capacitor 34 to the grid 11g of tube 11. The grid 11g is connected to the grounded end of resistor 16 through a resistor 35 from which it receives its signal voltage and a resistor 36 from which it receives its automatic control voltage. These resistors are so related that for weak signals the grid 11g is more negative than the grid 10g. The control currents in the resistors 31 and 36 are so poled that the signal increases the negative bias of grid 10g and decreases the negative bias on grid 11g and the bias values approach each other as the signal is increased. Because of the phase reversal effect of the signal by the tube 23, the overall gain of the system is diminished as these changes of bias occur.

The plates 10a, 11a of tubes 10 and 11 are connected to ground through blocking capacitor 40 and a volume control potentiometer 41. Output terminals 42 and 43 are connected respectively to a variable tap 44 of the potentiometer 41 and ground. To provide for automatic change of bias of the tubes 10 and 11, a dynamic control potentiometer 45 is provided, one end of which is grounded, the other end of which is coupled through a capacitor 46 to the arm of a double throw switch 47 having two fixed contacts 48 and 49 connected to the grid 11g and the plate 11a respectively. The tap 50 of the potentiom-

eter 45 is connected by a lead 51 to the grid 52g of a rectifier driver tube 52, the cathode 52c of which is connected to ground through a resistor 53 shunted by a capacitor 54. The plate 52a of tube 52 is connected through a feed resistor 55 and decoupling resistor 56 to the positive end of battery 13. The junction of resistors 55 and 56 is connected to ground by bypass capacitor 57 and is connected through bleeder resistor 58 to the cathode 52c.

The plate 52a of the rectifier driver tube 52 is connected through capacitor 60 to the cathode of a rectifier 61, the anode of which is connected through a resistor 62 to the grid side of resistor 31. The anode and cathode of the rectifier 61 are connected respectively by resistors 63 and 64 to the cathode side of resistor 31. Resistors 31 and 63 are bypassed by capacitors 65 and 66 respectively.

Similarly the plate 52a of the rectifier tube 52 is connected through capacitor 70 to the anode of a rectifier 71 the cathode of which is connected through a resistor 72 to the grid side of resistor 36. The anode and cathode of the rectifier 71 are connected through resistors 73 and 74 to the cathode side of resistor 36. Resistors 36 and 74 are bypassed by capacitors 75 and 76 respectively.

In the operation of this system for weak signals the voltage on the grid 10g is substantially equal and opposite to the voltage on the grid 11g, but tube 10 is more effective in producing amplified output than tube 11 due to its lesser negative bias. Therefore weak signals are amplified well. However, as the signal increases, the rectifier driver tube 52 is actuated by the output signal derived from the potentiometer 45, which automatically changes the bias on the grids of tubes 10 and 11 in such a fashion that the difference in amplifying ability is reduced, and the gain of the system as a whole for strong signals is less than for weak signals. The constants of the rectifier system are so chosen that the control of bias is substantially in accordance with the acoustical value of the output signal; so that the rectified outputs of devices 61 and 71 are not excessive; so that the D. C. component of the current through feed resistor 12 is substantially independent of signal level; and so that the amplification produced by the system follows the increase and decrease of signal level in a smooth manner.

If desired, the switch 47 may be closed to the contact 48 so that the gain of the amplifier may be controlled by the acoustic level of the input signal instead of the acoustic level of the output signal. Limiters may be used and so adjusted that for strong signals the gain of the two tubes may approach cancellation to any desired degree. The shape of the curve relating output decibels to input decibels may be controlled by design to meet various requirements, by use of limiters and by use of over biasing the rectifier driver 52 or by biasing the rectifiers 61 and 71. Various other modifications may be made by those skilled in the art.

Although only a few of the various forms in which this invention may be embodied have been shown herein, it is to be understood that the invention is not limited to any specific construc-

tion but might be embodied in various forms without departing from the spirit of the invention or the scope of the appended claim.

What is claimed is:

- 5 A compressor amplifier system comprising a pair of electronic tubes having plates, cathodes and control grids, said plates being connected together and said cathodes being connected together to provide parallel space current paths, 10 a common output circuit connected between said plates and a point of fixed reference potential, a source of direct-current plate voltage having a positive and a negative terminal, said negative terminal being connected to said point of fixed 15 reference potential, a common feed resistor connected between said plates and said positive terminal, a common cathode impedance comprising two series connected cathode resistors connected between said cathodes and said point of fixed reference potential, an input circuit including a phase inverter tube having a plate, a control grid and a cathode, said phase inverter plate being connected to the grid of the first of 20 said pair of electronic tubes, said phase inverter cathode being connected to the grid of the second of said pair of electronic tubes, whereby to impress signals upon said control grids in phase opposition, a first pair of serially connected grid resistors connected between the control grid of the first of said pair of electronic tubes and the common connection of said cathode resistors, a second pair of serially connected grid resistors connected between the control grid of the second of said pair of electronic tubes and said point 25 of fixed reference potential, whereby different biasing potentials are applied to the respective electronic tube control grids, a rectifier driver amplifier circuit having an input circuit and an output circuit, said rectifier driver input circuit being connected to said common output circuit and including selective switching means responsive to the signal voltage to actuate said rectifier driver, a pair of rectifiers, said rectifiers being connected to said rectifier driver output circuit in oppositely poled relation, and a resistor-capacitor network connected with each of said rectifiers, one of said networks being connected with one of said grid resistors of said first pair 30 of serially connected grid resistors, the other of said networks being connected with one of said grid resistors of said second pair of serially connected grid resistors, whereby control voltages are applied to said shunt connected tubes in opposite sense so that an increase in control voltage decreases the difference in bias on the respective grids whereby the output signals are brought more nearly into balance and the amplification of the system is decreased with increased input signal level.
